BOTTLE HOLDER

James C. Kelley, Trinity, Tex.

Application May 31, 1951, Serial No. 15,355

Term of patent 14 years

(Cl. D58—26)

To all whom it may concern:

Be it known that I, James C. Kelley, a citizen of the United States of America, residing at Trinity, in Trinity County, State of Texas, have invented a new, original, and ornamental Design for a Bottle Holder, of which the following is a specification, reference being made to the accompanying drawing, forming a part thereof.

Fig. 1 is a perspective view of the top and one side of the bottle holder showing my new design; and Fig. 2 is a perspective view of the top and the other side thereof.

I claim:

The ornamental design for a bottle holder, as shown.

J. C. KELLEY,
